UNITED STATES PATENT OFFICE.

WILLIAM BING, OF SANDUSKY, OHIO.

SINGLE OR DOUBLE TREE.

SPECIFICATION forming part of Letters Patent No. 430,765, dated June 24, 1890.

Application filed August 26, 1889. Serial No. 322,047. (No model.)

To all whom it may concern:

Be it known that I, WILLIAM BING, of Sandusky, in the county of Erie and State of Ohio, have invented certain new and useful 5 Improvements in Single or Double Trees; and I do hereby declare that the following is a full, true, and exact description thereof.

My invention relates to that class of single-trees or doubletrees which are provided with 10 a tension mechanism for the purpose of avoiding sudden jerks in the attempt of starting heavily-loaded trucks or wagons, and thereby releasing the team from the strains, jars, and galling on the shoulders to which animals 15 are subjected in drawing loads in the ordinary way.

The invention consists in the particular as well as peculiar construction of a doubletree, the object of which is to combine simplicity 20 in a reliable, effective, and durable mechanism; and that the invention may be fully understood reference will be had to the annexed specification and the accompanying drawings, in which—

25 Figure 1 is a face view of a doubletree provided with the improvements above referred to. Fig. 2 is a side view of the same. Fig. 3 represents a sectional view on line $x x$, Figs. 1 and 2. Fig. 4 is an end view of said double- 30 tree, and Fig. 5 is a detached section of the central part thereof.

Like letters of reference denote like parts in the drawings and specification.

The implement as represented is more especially adapted to be used as a doubletree 35 than a singletree. It may, however, be applied as such.

In the drawings, A A designate the bare sections of the doubletree; B, the spring as 40 an entirety; C C, the links, and D D the loops, which together substantially constitute the doubletree. The adjoined ends of the sections A A are provided with plates E E, E' E', and F, which are held united and attached to said sections by means of the bolts 45 G G and H H, as seen in Figs. 1 and 2.

By means of the plates E E the sections A A are held in proper relation with and to each other, while the bolts G G allow of lateral vibration thereof to make use of the tension of the spring B for the purpose above referred to. The ends of the sections are notched at a a to conform with the holes a' a' of the plates E E, through which the king-bolt is extended in connecting the double-

tree to the wagon or truck for which it is intended. The plates E' E' and F prevent the wooden sections A A from splitting and also preserve them from being prematurely worn away by the parts with which they are brought 60 in contact.

In Fig. 1 the upper of the plates E is shown in dotted lines in a removed position to enable view of the parts underneath the same.

The spring B consists of a series of leaves 65 b, which are held united by means of the clip c, as seen in Figs. 1 and 3. The free ends of the upper leaf thereof are rolled up to receive the bolts I I, by means of which connection with the links C C is had. 70 The links themselves are hinged to each of the sections A A by means of the bolts J J to set said sections in operative relation to the spring B—that is, applying the tension thereof for the purpose of avoiding sudden jerks 75 in starting the truck to which the doubletree is attached. The projection d of the clip c extends into corresponding depressions of the sections A A, and thereby retains the clip in proper position—that is, centrally upon 80 the line of contact of said sections—to exert equal resistance upon the same. Fig. 5 represents the central portion of the whiffle-tree, with the plates E in proper place.

The loops D D for attachment of the whiffle-trees are or may be of the usual style. The hooks K K (seen in Figs. 1 and 4) are to be considered as merely auxiliary appendages, as is customary to supply doubletrees with. 85

90 What I claim, and desire to secure by Letters Patent, is—

A double or single tree, consisting of the sections A A, plates E E, spring B, and links C C, the said sections being provided with 95 plates E' E' and F, and notches a a at one end for connection with the plates E E, and loops D D at the free ends, the spring B, composed of a series of leaves held united by the clip c, and links C C for attachment 100 of said beams and spring, constructed and arranged substantially as and for the purpose set forth.

In testimony whereof I affix my signature in presence of two witnesses.

WILLIAM BING.
